UNITED STATES PATENT OFFICE.

HUGO ERNST, OF CAMDEN, NEW JERSEY.

COLLAPSIBLE LIFE-BOAT.

1,146,059.

Specification of Letters Patent. Patented July 13, 1915.

Application filed September 26, 1914. Serial No. 863,673.

To all whom it may concern:

Be it known that I, HUGO ERNST, a citizen of the United States, residing at Camden, in the county of Camden and State of New Jersey, have invented new and useful Improvements in Collapsible Life-Boats, of which the following is a specification.

The invention relates to boats, and more particularly to the class of collapsible life boats.

The primary object of the invention is the provision of a boat wherein the same when not in use can be readily folded into compact form so that any number of the boats may be stored in a comparatively small area, the construction of the boat insuring strength when in open position for use.

Another object of the invention is the provision of a boat of this character where- 20 in the construction thereof is of novel form so that it can be readily and easily folded and unfolded.

A further object of the invention is the provision of a boat of this character which is extremely simple in construction, reliable and efficient in its purpose, and inexpensive in manufacture.

With these and other objects in view, the invention consists in the construction, combination and arrangement of parts as will be hereinafter fully described, illustrated in the accompanying drawings, and pointed out in the claims hereunto appended.

In the drawings: Figure 1 is a top plan view of a boat constructed in accordance with the invention. Fig. 2 is a vertical longitudinal sectional view thereof. Fig. 3 is a transverse sectional view on the line 3—3 of Fig. 1. Fig. 4 is a similar view 40 showing the boat collapsed. Fig. 5 is a detail horizontal sectional view on the line 5—5 of Fig. 2. Fig. 6 is a detail perspective view of one of the floor sections. Fig. 7 is a detail sectional view on the line 7—7 of Fig. 2. Fig. 8 is an enlarged sectional view 45 taken through the floor of the boat.

Similar reference characters indicate corresponding parts throughout the several views in the drawings.

Referring to the drawings in detail, the collapsible boat comprises a foldable frame including fore and aft keel pieces 1 and 2, respectively, to which is secured a metallic strap 3 extending the entire length of the frame, the ends of the strap 3 being inset in the keel pieces so as to form a flush joint

therebetween, the outwardly bowed braces 4, 5 and 6 constituting each side of the frame and are connected to the keel pieces 1 and 2 through the medium of double 60 hinges 7 which allow the said braces to lie flush with the sides of the boat when the same is in an open position, and also permit the sides of the frame to be brought together when the boat is collapsed.

Supported upon the strips 6 and connected thereto through the medium of hinges 8 are floor sections 9, the free or meeting end edges of the latter being formed with the usual tongue and groove 10 and 11 so 70 that the meeting ends of the said sections will overlap one another and thereby afford a strong floor with flush surfaces when the boat is in open position. The meeting edges of the floor sections 9 are connected through 75 the medium of hinges 11' so that on the folding of the boat the floor thereof will fold outwardly into the position as shown in Fig. 4 of the drawings.

Covering the frame is a canvas or other 80 suitable fabric sheeting 12 which is firmly fastened to the said frame and is reinforced along the inner side thereof with wire netting 13, thus holding the same flexible but rigid. Located within the frame and cover- 85 ing the area of the bottom thereof is a pneumatic bag 14, the bag being disposed between the strip 3 which serves as the keel and the floor sections 9, and is adapted to be inflated or filled with air when the boat 90 is extended so as to render the same non-sinkable. The bag 14 is provided with a valved nipple 15 which permits the filling thereof with air, and the said nipple is ex- 95 tended through a suitable opening in a pair of adjacent floor sections so as to make it readily accessible for the application of a pump or other device when it is desired to fill the bag with air for inflating the same.

Above the floor at a suitable height are 100 arranged folding seats 16 which are pivotally secured to the strips 4 by means of hinges 17, each seat being formed in two parts swingingly connected at its center through the medium of hinges 18, the hinged 105 joints at the center of each seat being pro- 110 vided with the usual tongue and groove to form a close fitting and flush joint when the seats are lowered. Swingingly connected to the two parts of each seat near the center joint thereof are legs 19 which are adapted to contact with the floor and serve to sup-

port the seat at the center thereof to prevent the sagging or the lowering of the seat when weight is applied thereto.

From the foregoing description, taken in connection with the accompanying drawings, it is thought that the construction of the device will be clearly understood, and therefore a more extended explanation has been omitted.

10. What is claimed is:—

1. A collapsible boat comprising fore and aft keel pieces, a keel strip connected to said pieces, double hinges connected to opposite sides of the keel pieces, outwardly bowed braces connected with the said hinges, a plurality of floor sections hinged to a pair of said braces and having break joints in alignment with the keel, an inflatable buoyant bag located between the floor sections and the keel, a flexible covering without and fixed to the respective keel pieces, keel and braces, and sectional hingedly connected seats pivotally secured to another pair of the braces and having break joints in vertical alignment with the break joints of the floor sections.

2. A collapsible boat comprising fore and aft keel pieces, a keel strip connected to said pieces, double hinges connected to opposite sides of the keel pieces, outwardly bowed braces connected with the said hinges, a plurality of floor sections hinged to a pair of said braces and having break joints in alignment with the keel, an inflatable buoyant bag located between the floor sections and the keel, a flexible covering without and fixed to the respective keel pieces, keel and braces, sectional hingedly connected seats pivotally secured to another pair of the braces and having break joints in vertical alignment with the break joints of the floor sections, and substantially U-shaped legs pivotally mounted on the seats and adapted to rest on the floor sections to prevent the sagging of the seats and also to prevent the outward folding of the said floor sections.

In testimony whereof I affix my signature in presence of two witnesses.

HUGO ERNST.
